3 SHEETS-SHEET 3.

UNITED STATES PATENT OFFICE.

CHARLES E. SIEVERT, OF COUNCIL BLUFFS, IOWA.

CAR-DOOR.

1,073,715.

Specification of Letters Patent. Patented Sept. 23, 1913.

Application filed August 7, 1911. Serial No. 642,635.

To all whom it may concern:

Be it known that I, CHARLES E. SIEVERT, a citizen of the United States, residing at Council Bluffs, in the county of Pottawattamie and State of Iowa, have invented certain new and useful Improvements in Car-Doors, of which the following is a specification.

This invention relates to car doors, and has for its object to provide an improved door of this character which may be readily and conveniently applied to an ordinary box car without requiring any material change or alteration therein beyond some slight additions for the mounting of the door.

The present door is designed to be mounted upon the interior of the car, and to serve as a grain door. It may be employed in conjunction with the ordinary outside door, and the ordinary outside door omitted and the present door only employed.

With these and other objects in view, the present invention consists in the combination and arrangement of parts as will be hereinafter more fully described, shown in the accompanying drawings and particularly pointed out in the appended claims, it being understood that changes in the form, proportion, size and minor details may be made within the scope of the claims, without departing from the spirit of the present invention.

In the accompanying drawings;—Figure 1 is an elevation, looking from the exterior of a car, of a door constructed in accordance with the present invention. Fig. 2 is a detail sectional view taken on the line 2—2 of Fig. 1. Fig. 3 is an elevation, looking from the interior of a car, of a door constructed in accordance with the present invention and on a scale smaller than that shown in Fig. 1. Fig. 4 is a detail sectional view on the line 4—4 of Fig. 3. Fig. 5 is a detail sectional view on the line 5—5 of Fig. 3, the upper door member being shown swung outwardly in dotted lines. Fig. 6 is a view similar to Fig. 3 showing the upper door member slid to one side of the door way, and the lower door member swung or tilted to the opposite side of the doorway. Figs. 7 and 8 are enlarged detail views showing the device for locking the upper sliding door section in its closed position. Figs. 9 and 10 are detail fragmentary views showing

means for locking the wickets of the upper and lower door members. Fig. 11 is an enlarged detail sectional view taken on the line 11—11 of Fig. 3.

Like characters of reference indicate corresponding parts in each of the several figures of the drawings.

The present invention includes an upper door member 1 and a lower door member 2, the upper door being mounted to slide horizontally in a direction longitudinally of the car to open and close the upper portion of the door way, while the lower door member 2 is mounted to swing or tilt vertically to one side of the doorway, so as to open and close the lower part thereof. The side 3 of the car is of ordinary construction and has an ordinary side doorway or opening 4, as clearly shown in Figs. 2 and 4.

The lower door member 2 consists of a single metal plate or sheet of suitable size to close the lower portion of the door way, preferably the lower half thereof, and this door member is stiffened and strengthened by intermediate angle bars 5, and upper and lower angle bars 6 and 7 secured to the outer face of the door. Upon the top of the horizontal member of the upper angle bar or iron is a facing strip 8, preferably of wood, the upper face of which is beveled downwardly and inwardly of the car as best shown in Fig. 5 of the drawings. This lower door member is pivotally supported at one of its lower corners, here shown as the lower right hand corner, looking from the interior of the car. To effect this pivotal mounting of the door, the latter is provided with a lateral extension or heel 9 which is hinged or pivoted in a suitable bearing 10 secured to the floor of the car, whereby the door may be swung or tilted upwardly and to the right, as indicated in Fig. 6 of the drawing. For the purpose of guiding the door in its tilting movement, there is provided an arcuate guideway 11, preferably in the form of a quadrant secured to the inner side of the car and spaced therefrom, said guideway being slidably engaged by a guide member 12 at the upper right hand corner of the door, this guide member working against the guideway and thereby holding the door from swinging away from the side of the car during tilting movements of the door. By preference, this guide mem-

ber 12 is in the form of a Z-bracket so as to engage beneath the guideway 11 and between the latter and the side of the car. The convexed edge of the guideway is toothed, as shown and is engaged by a gravity detent 13 pivoted to the upper right hand corner of the door member, whereby the door may be held in any tilted position, as indicated by dotted lines in Fig. 6, so long as the center of gravity of the door is at the left hand side of the pivotal support of the door. The guide bracket 12 and the detent 13 are carried by a lateral extension 14 of the upper right hand corner of the door member 2. When the door member 2 has been swung to its open position, the extension 12 rests against the floor of the car, while the other corner of the door engages back of the keeper 15 secured to the inner side of the car. To prevent oscillation of the tilting door in its open position, a swinging gravity detent 16 is pivoted to the inner side of the car in position to engage what is the upper edge of the door member in its open position, as clearly shown in Fig. 6 of the drawing. Any suitable handle *a* is provided upon the inner side of the door member 2 for swinging the same into open and closed position.

It will here be noted that, at each end of the guideway 11, the teeth are omitted for a suitable extent. When the tilting door 2 is moved into its closed position, the swinging dog or detent 13 escapes from the teeth at the upper end of the guideway and hangs vertically in the seat or recess provided at the upper end of the guideway by the omission of the teeth, whereby the detent is in a position to reengage the teeth of the guideway when the door is again swung open and be in a position to hold the door in any tilted position. When the door is swung to its open position, the detent again escapes from the teeth at the lower end of the guideway, and is free to reengage the teeth when the door is tilted back to its closed position. The provision of teeth upon the guideway 11 is also a very important feature, when it is considered that the door is very heavy and is accessible for opening from the exterior of the car only. After the car has been partially unloaded through the wicket 37 and the door 1 slid horizontally into an open position, the lower tiltable door may be opened to a slight extent by prying up the same from the exterior of the car. As the door is pried up a little at a time the detent 13 will engage the teeth on the guideway and thereby hold the door from dropping back into its closed position, which obviates the necessity of manually holding the door while prying it open.

To effect a grain tight fit of the lower door member 2 with the sides of the doorway, the free edge of the door, which is opposite the

pivotal support 10, is beveled, as shown at 17 in Fig. 4, and an upright strip 18 is secured to the inner side of the car and is provided with a beveled rabbet 19 constituting a seat for the reception of the beveled edge 17 of the door member. At the hinged edge of the door and upon the outer face thereof, there is a vertical strip 20 which engages in the closed position of the door with a vertical strip 21 secured to the inner side of the car, the meeting faces of these strips being beveled so as to form a tight joint.

The upper door member 1 is made up of a single metal sheet or plate, and is stiffened and strengthened by intermediate transverse angle-irons or bars 22 and upper and lower angle bars 23 and 24. Upon the lower face of the lower angle bar 24 is a wooden strip 25 having a beveled face which fits tightly against the beveled face 8 of the wooden strip upon the top of the lower door member so as to form grain tight fit between the meeting edges of the door members. Suitable hangers 26 are provided at the upper corners of the door member 1, and these hangers have a sliding and rotatable fit upon a guideway 27 secured to the inner side of the car and extending across the top of the doorway and for a suitable distance beyond one side thereof opposite the pivotal support of the lower door member.

To effect a tight joint between the upright edges of the upper door member 1 and the sides of the car, in the closed position of the door, beveled strips 28 are secured to the outer face of the door member at its upright edges so as to engage correspondingly beveled strips 29 secured to the inner walls of the car. To disengage the door member from the strips 29, the door member is swung inwardly upon the guideway 27 as a support, as indicated by dotted lines in Fig. 5 of the drawing, whereupon the door member may be slid upon the guideway and moved to one side of the doorway to the position shown in Fig. 6. A suitable handle 30 is provided upon the inner side of the door member 1 for manipulating the door, and a handle 31, shown in Fig. 1, is provided upon the outer side of the door for convenience in manipulating it from the exterior of the car.

To lock the upper door member in its closed position, there is provided, as best shown in Figs. 7 and 8, a pivotal latch 32 mounted upon one of the door posts and designed to engage a keeper 33 provided upon the outer side of the upper door member 1, there being a swinging detent 34 pivoted to the outer face of the door member above the keeper in position to engage the top of the latch 32 and hold it down in the keeper. The detent 34 and the latch 32 are provided with ears 35 and 36 respectively, having aligned perforations for the reception of any common or preferred form of seal, such for

instance as the ordinary wire seal employed for sealing box cars. It will of course be understood that one of these latch devices is provided upon each door post, as plainly indicated in Figs. 1 and 6 of the drawing.

When the two door members are in closed position, the lower door member is held against accidental tilting by reason of the fact that the upper door member engages snugly across the upper edge of the lower door member, and as the upper door member is held against accidental movement by the two latches 32, the two door members are positively held in closed position.

To open the door, the latches 32 are disengaged from the keepers, and the upper door member is then swung outwardly to disengage the strips 29 and then the upper door member is slid to one side of the doorway, after which the lower door member may be tilted to its open position shown in Fig. 6.

The lateral extensions 9 and 14 bring about an important feature, in that any slight accumulation of grain, coal or the like adjacent the pivotal support of the tilting door will not prevent the complete opening of the door, for the reason that the lateral extensions 9 and 14 hold the intermediate edge portion of the door above the floor of the car in the open position of the door. Moreover, the lateral extension 14 will crush small accumulations of grain, coal or the like, by reason of the considerable weight of the door, and thereby permit the door to open to its complete extent.

The upper door member is provided with a wicket 37, and the lower door member is provided with a wicket 38, each of which is suitably hinged to its door member, the wicket 37 being hinged at its lower edge, and the wicket 38 hinged at its upper edge.

For holding each wicket in its closed position, any preferred latch means may be employed, a suitable arrangement being shown in detail in Figs. 9 and 10. At each upright edge of the wicket there is a latch bar 37 which projects beyond the free edge of the wicket and is designed to be engaged back of a vertically movable gravity bolt 38 working in a suitable casing 39 provided upon the adjacent door member, the lower end of the bolt projecting below the casing having a beveled lower end portion 40 across which the latch member 37 wipes, during the closing of the wicket so as to lift the bolt, said bolt afterward dropping down in front of the latch to lock the wicket. The upper projecting end of the bolt is provided with a transversely extending headed handle 41 which may be engaged with a swinging link 42 carried by the door so as to hold the bolt in an elevated position when it is desired to open a wicket.

For convenience in opening the bottom tilting door member 2 from the exterior of

the car, a suitable handle 43 is provided upon the exterior of the door member, as best shown in Fig. 1 of the drawings.

The engagement of the guide bracket 12 of the door 2 with the arcuate guide 11 will be best understood by reference to Fig. 11 of the drawings, wherein it will be seen that the guide bracket 12 extends laterally from the floor and is provided in its upper edge with a seat or socket 12' receiving the lower concaved edge of the guide. By this means the door 2 is held in a vertical plane and prevented from swinging sidewise away from the side of the car.

What is claimed is:—

1. A vertically tiltable door having a swinging gravity detent, and a member supported independently of the door and provided with a toothed convexed portion struck from the pivotal support of the door as its center, said toothed portion lying in the path of the free end of the detent for engagement thereby to support the door in tilted position, the toothed portion terminating at each end short of the path of movement of the door to permit the detent to swing clear of the teeth at the opposite limits of movement of the door, substantially as described.

2. A vertically tiltable door pivotally supported at one of its lower corners and having a swinging gravity detent, a member supported independently of the door and provided with a toothed convexed portion struck from the pivotal support of the door as a center, said toothed portion lying in the path of the free end of the detent for engagement thereby to support the door in tilted positions, and a slide carried by the door and engaging the toothed member as a guide, substantially as described.

3. A vertically tiltable door pivotally supported adjacent one of its lower corners and provided with a swinging gravity detent, an arcuate guide member supported independently of the door and disposed in an arc struck from the pivotal support of the door as a center, the convexed edge of the guide being toothed and said toothed portion terminating short of the ends of the guide and lying in the path of the free end of the detent, and a slide carried by the door and embracing the concaved edge of the guide, substantially as described.

4. A door including a vertically tiltable door member pivotally supported at one of its lower corners, an arcuate guide member disposed concentric to the pivotal support of the door, a slide carried by the door and co-operating with the concaved side of the guide, and a swinging gravity detent carried by the door and co-operating with the convexed side of the guide to hold the door in different tilted positions, substantially as described.

5. A vertically tiltable door provided with a pivotal support adjacent one lower corner, a swinging gravity detent upon the door, a member supported independently of the door and provided with a convexed toothed portion disposed in an arc struck from the pivotal support of the door as a center and disposed in the path of the free end of the detent, the ends of the toothed member terminating short of the ends of the path of the detent, whereby the latter will clear the toothed portion and be free to reengage the same when the movement of the door is reversed, substantially as described.
- 10 6. A vertically tiltable door provided with a pivotal support adjacent one lower corner, a swinging gravity detent upon the door, a member supported independently of the door and provided with a convexed toothed portion disposed in an arc struck from the pivotal support of the door as a center and disposed in the path of the free end of the detent, the ends of the toothed member terminating short of the ends of the path of the detent, whereby the latter will clear the toothed portion and be free to reengage the same when the movement of the door is reversed, and a swinging gravity detent sup-
- 15 20 25

ported independently of the door and disposed in the path of that edge of the door which is opposite the pivotal support of the door, substantially as described.

7. A vertically tiltable door provided with a lateral extension at the top of one of its upright edges, another lateral extension on the same upright edge of the door and at the bottom thereof, and a pivotal support for said extension, substantially as described.

8. A vertically tiltable door provided with upper and lower lateral extensions at the same upright edge of the door, a pivotal support for the lower extension, a gravity detent pivoted upon the upper extension, a slide carried by the upper extension, and an arcuate toothed guide having its toothed portion disposed in the path of the free end of the detent and its concaved edge engaged by the slide, substantially as described.

In testimony whereof I affix my signature in presence of two witnesses.

CHARLES E. SIEVERT.
